UNITED STATES PATENT OFFICE

FREDERICK W. PETERSON, OF BROOKLYN, NEW YORK, ASSIGNOR TO HORTON SWEETS CO. INC., OF RIDGEFIELD, NEW JERSEY, A CORPORATION OF NEW YORK

DESIGN FOR A CARTON OR SIMILAR CONTAINER

Application filed October 29, 1928. Serial No. 28,685. Term of patent 3½ years.

To all whom it may concern:

Be it known that I, FREDERICK W. PETERSON, a citizen of the United States and a resident of the city of New York, in the county of Kings and State of New York, have invented a new, original, and ornamental Design for a Carton or Similar Container, of which the following is a specification.

My design for a carton or similar container is clearly illustrated in the accompanying drawing wherein—

What is claimed is:

The ornamental design for a carton or similar container as shown.

Signed at New York, in the county of New York, and State of New York this 23d day of October, A. D. 1928.

FREDERICK W. PETERSON.
